GEORGE KOCH, OF PATERSON, NEW JERSEY, ASSIGNOR TO ERNEST CADGENE AND OLAV BERG, BOTH OF PATERSON, NEW JERSEY.

PILE FABRIC.

1,342,589.

Specification of Letters Patent. Patented June 8, 1920.

Application filed January 21, 1919. Serial No. 272,344.

To all whom it may concern:

Be it known that I, GEORGE KOCH, a subject of Germany, residing at Paterson, in the county of Passaic and State of New Jersey, have invented certain new and useful Improvements in Pile Fabrics, of which the following is a specification.

This invention relates to weaving and it consists in a pile fabric formed with an uncut pile and with shots of filling extending through the portions of the rows of pile loops which project from the ground, the filling length represented by each such shot and one of the filling lengths in the ground being continuations of each other.

Figure 1 shows in longitudinal section the improved pile fabric; and

Figs. 2 and 3 illustrate also in longitudinal section how the pile fabric shown in Fig. 1 may be woven.

The fabric is composed of warp threads *a a'* (those designated *a'* being utilized to form the pile) and lengths or shots of weft or filling. One method of forming the fabric is shown in Figs. 2 and 3, which illustrate the forming of two fabrics face to face at once, with separate warps *a a'* and filling *b* and by the use of two weft carriers, and also by the use of attenuated supports *n* which are suitably secured at their rear ends but have their forward ends free, and which are arranged in a series which extends transversely of the two warps and between them and the paths of movement of the two weft carriers. The said supports are secured at their rear ends and have their forward ends free so that as the fabrics are formed and move forward they will clear the supports, as will appear. The ground for each fabric may be woven in any way so as to form crossings of the warp threads with the lengths of filling *b* between such crossings. From time to time, as the weaving proceeds and as to each fabric, the pile warp threads *a'* are made to form sheds with the series of supports *n*, through which shed the relatively opposite weft carrier is shot, and when the pile warp threads *a'* are then returned past said supports to be again continued in the weaving of the ground the length of weft or filling *b* which was passed through said shed is left supported by said supports and so forms a row of pile loops *C*, the supporting of said length of filling *b* by the supports *n* continuing until in the

advance of the fabric as the weaving proceeds said length of filling clears the free ends of said supports. To avoid the pile rows coupling the two fabrics together, the pile shed forming operations, one for each fabric, do not occur at the same time, but alternately, so as to avoid the resultant rows of pile loops both receiving the same shots of filling; and when the pile shed for either fabric is formed all the warp threads for the other fabric are withdrawn from between the path of their corresponding weft carrier and the plane of the supports *n*, so as to avoid the resultant row of pile loops being connected at their free ends or submits to the latter fabric. In the specific form of fabric resulting from the particular method of weaving herein assumed each fabric has two filling lengths in each of its rows of loops, one being delivered by the same weft carrier that introduces filling lengths into the ground of that fabric and the other being delivered from the carrier that delivers filling lengths into the ground and rows of pile loops of the other fabric. Fabrics woven as in Figs. 2 and 3, though not interconnected as to their pile loops, will be interconnected at their edges, as will be apparent where those of the portions of filling marked *x* in Fig. 2 (represented by arrows to indicate the general course of the filling at the near edge of the fabric) run from the ground of one fabric to the pile loops of the other, and to separate the fabrics it will obviously only be necessary to sever at some point the connections thus developed.

It will be noted that each filling length in a row of pile loops and another filling length (to wit, in the ground) are continuations of each other and that they will further be left as such if only the portions of filling marked *x* which actually form the connections aforesaid are severed, *i. e.*, so as to leave intact each group of filling lengths designated 1, 2, 3, 4.

Because by the method of weaving my fabric herein set forth the thickness of the filling and in addition of the supports *n* determines the height of the pile, it will be obvious that in the finished fabric of my invention the space of each loop is somewhat greater than the thickness of the filling extending through it, wherefore the filling is more or less loose or free therein,

which is an advantage of great value for some of the purposes to which the fabric may be put in that while the loops are as it were padded they are not stretched or dis-tended and are thus better adapted to resist wear.

Having thus fully described my invention, what I claim and desire to secure by Letters Patent is:

10 A woven pile fabric including warp threads and filling lengths forming the ground of

the fabric and also having some of the warp threads forming rows of pile loops project-ing from the ground and filling lengths ex-tending through the projecting portions of 15 the loops of such rows, each filling length in a row of pile loops and one of the filling lengths in the ground being continuations of each other.

In testimony whereof I affix my signature. 20

GEORGE KOCH.
